UNITED STATES PATENT OFFICE

ROY MARTELL MASON, OF BATAVIA, NEW YORK, ASSIGNOR TO F. E. MASON & SONS, OF BATAVIA, NEW YORK, A CORPORATION OF NEW YORK

TAG

Application filed July 25, 1931. Serial No. 553,180.

This invention relates to improvements in tags of the type sometimes used to identify pieces of jewelry and the like by attachment thereto.

5 It is an object of this invention to provide a decorative and useful tag of the type described which is not only attractive in appearance, but which is very serviceable and may be quickly and easily installed and removed from the article on which it is installed, but which when installed will not accidentally become separated from such article.

This and other objects of the invention, its nature, and its composition and arrangement 15 and combination of parts will be readily understood by any one acquainted with the art to which this invention relates upon consulting the following descriptions of the drawings, in which:—

20 Figure 1 is a plan view of the tag of the invention.

Figure 2 is a similar view of the invention in folded and engaged position.

Figure 3 is a vertical transverse sectional 25 view taken approximately on the line 3—3 of Figure 2.

Figure 4 is a horizontal sectional view taken approximately on the line 4—4 of Figure 2.

Referring in detail to the drawings, it will 30 be seen that the device of the invention consists of a pair of disks 5, 6 each of which may be provided with the form of an embossed or stamped seal, the disks being connected at one edge by a perforated or weakened joint

35 7, so as to provide for easy folding at the joint 7 so as to bring the disks 5 and 6 into the superposed relation seen in the remaining figures of the drawings. The seal 6 is provided with a radial projection 8 which has

40 a half moon or semi-circular cut 9 therein, weakened as at 10, and on the radially outward extremity of the projection 8 there is formed a finger 11 provided with a laterally enlarged semi-circular head 12. Midway of 45 the ends of the finger 11 there is provided a weakened area 13 to facilitate bending the finger as in Figure 2, in the case of the use of the device for clipping papers together, where the spacing between the portions of

50 the bent finger 11 is not great.

Either disk may be folded on the perforated area 7 so as to bring it into superposed relation upon the other disk as seen particularly well in Figures 3 and 4. When this has been done a tab 14 provided on the disk 6 and connected thereto by another weakened area 15 is in position to be bent around the edges of the disks 5 and 6 to retain them together as shown in Figure 4.

The finger 11 is adapted to be inserted through a ring, a hole or is otherwise suitably passed through an aperture or part of an article to be tagged, and then the head is inserted through the cut 9 in the projection 8, in such a way that the lateral extensions 60 of the head 12 will catch against the edges of the cut 9 and be returned thereby. The tab 16 resulting from the cut 9 is then bent so as to retain the head 12 in an obvious manner as shown in Figures 2 and 3, locking the 65 head 12 in the cut 9.

It is believed that the above sufficiently describes the invention to enable any one acquainted with the art to which the invention relates to make and use the same, and 70 further description therefor will not be given.

It is to be definitely understood that I do not desire to limit the application of this invention to the particular form set out herein to illustrate the principles thereof, and any change or changes may be made in material and structure and arrangement of parts consistent with the spirit and scope of the invention.

80 What is claimed is:—

1. A tag of the type described comprising a pair of disks connected edge to edge and adapted to be folded upon each other at their juncture, a radial projection on one of the disks, a cut in said projection defining a tab, a headed finger on the projection adapted to be threaded through an aperture in an article, to secure the tag to said article and then bent upon itself so as to permit insertion of the headed portion of the finger through said cut, said tab adapted to be bent to confine the headed portion in the cut.

2. A tag of the type described comprising a pair of disks connected edge to edge and

adapted to be folded upon each other at their juncture, a radial projection on one of the disks having a cut defining a tab, a headed finger on the projection adapted to be threaded through an aperture in an article, to secure the tag to said article and then bent upon itself so as to permit insertion of the headed portion of the finger through said cut, said tab adapted to be bent to confine the headed portion in the cut, and another tab on said one of the disks adapted to be bent to retain the disks together when folded upon each other.

3. A tag of the type described comprising a pair of disks connected edge to edge and adapted to be folded upon each other at their juncture, a radial projection on one of the disks having a cut defining a tab, a headed finger on the projection adapted to be threaded through an aperture in an article, to secure the tag to said article and then bent upon itself so as to permit insertion of the headed portion of the finger through said cut, said tab adapted to be bent to confine the headed portion in the cut, and another tab on said one of the disks adapted to be bent to retain the disks together when folded upon each other, said tag being constructed from a single piece of material.

30. In testimony whereof I affix my signature.
ROY MARTELL MASON.
